UNITED STATES PATENT OFFICE.

EDWARD L. DA ROZA, OF ELK GROVE, CALIFORNIA.

SELF-SERVING STORE.

1,313,794.

Specification of Letters Patent. Patented Aug. 19, 1919.

Application filed November 7, 1918. Serial No. 261,498.

To all whom it may concern:

Be it known that I, EDWARD L. DA ROZA, a citizen of the United States, residing at Elk Grove, in the county of Sacramento and 5 State of California, have invented certain new and useful Improvements in Self-Serving Stores, of which the following is a specification.

This invention relates to stores for vending groceries and other merchandise and more particularly to that class of stores in which the service of selecting and collecting the different articles or commodities is performed by the individual purchasers and 15 commonly known as self-serving stores.

The object of the invention is to provide a store or sales room, the interior construction or display arrangement of which is such as to utilize a maximum floor space 20 or area for the display of merchandise and to so arrange the display cabinets or shelves as to permit a customer to conveniently inspect the entire stock of goods and make his desired selections therefrom in less time 25 than heretofore.

The invention further aims to provide a novel system of aisles between the display cabinets or shelves, said aisles being connected by intermediate passageways and 30 each aisle being provided with a central partition or rail which not only serves to direct customers in a proper path through the store, but also compels said customers to make their selections of goods from the 35 shelves or cabinets on one side of each path only so that liability of overlooking any particular brand or kind of goods is reduced to a minimum.

The invention further aims to minimize 40 the congestion which might result from the loitering or visiting of customers while they are within the paths, and yet gives the greatest possible privilege to neighbors and friends who may speak or chat with each 45 other without necessarily retarding the progress of others who may wish to continue hurriedly from entrance to exit.

The invention further contemplates the provision of a basket rack or stand arranged 50 in alinement with and forming a part of one wall of the entrance lobby, said basket rack being readily accessible to customers entering the store room and to the clerk in charge of the wrapping and settlement department so that after the baskets have been 55 turned in by the customers they may be

conveniently and accurately replaced in the receiving rack by the settlement clerk without the necessity of him leaving his particular department.

60

A further object is to provide a store equipment including in its organization a general supply or stock room and a private office or auditing room, both being accessible from the sales department and the exterior 65 of said rooms being provided with shelving constituting a part of the display shelving of the sales department.

A still further object of the invention is generally to improve the construction and 70 arrangement of stores of this character so as to increase their utility and efficiency.

Other and incidental objects will appear as the description proceeds. In the drawings wherein I have illustrated the preferred embodiment of the invention, and wherein similar reference characters designate corresponding parts throughout the several views:

Figure 1 is a front elevation, partly in 80 section, of a self-serving store constructed in accordance with the present invention and looking rearwardly from the lobby thereof,

Fig. 2 is a horizontal plan view.

85

The improved store forming the subject-matter of the present invention comprises a preferably rectangular structure including side walls 5 and 6 connected by front and rear walls 7 and 8. Spaced from the front wall 7 is a transverse partition 9 defining independent compartments, one of which constitutes a lobby 10 and the other a sales room, indicated at 11. The partition 9 is provided with an entrance passage 12 and an exit 13 separated from each other by a suitable barrier 14, there being turnstiles 15 and 16 mounted for rotation in the entrance and exit passages, as best shown in Fig. 2 of the drawings, and through which the customers enter and leave the store, it being understood that the turnstile 15 will be provided with suitable ratchet mechanism so as to cause said turnstile to open inwardly only and the turnstile 16 provided with 100 ratchet mechanism to permit it to open outwardly only.

Within the salesroom are built a plurality of merchandise shelves, racks, or more specifically cabinets 17 as shown herein, which cabinets may be double-sided so that they face in opposite directions to display the 110

articles within them or upon their shelves. Each cabinet is composed of a row of units, preferably two in number, and the rows stand parallel with and are spaced from 5 each other to produce intervening aisles 18 extending longitudinally of the room 11 from one end wall to the other. The outer ends of the endmost units of the row abut the end walls of the room while their inner 10 ends are spaced from each other to produce a transverse opening 19, and when there are two units in each row the several openings 19 will align and produce a transverse aisle across the room at about its midlength inter- 15 secting all the longitudinal aisles 18.

Extending longitudinally within each aisle 18 and medially thereof are partitions which may be in the form of fences or rails 20 each having its outer end spaced from 20 the adjacent end of the aisle to form a return passageway 21 and its inner end connected by a diagonal portion or bar 22 with the adjacent merchandise holder 17 to form an oblique or cross-over passage 23. The 25 partitions may take any appropriate form. In some cases they may be of wood or other material, as high or as low as thought wise. But as a closed partition would to an extent shut off ventilation and render cleaning of 30 the store-room difficult, I prefer to make these partitions in the form of fences, and even in some cases in the form of hand rails. Whatever their construction, these elements 20 not only serve to direct customers in a 35 proper path through the store, but also compel the customers to make their selections of goods from the shelves or cabinets on one side of each path only so that liability of the customer overlooking any particular 40 brand or kind of goods is reduced to a minimum. In other words, with rather high partitions located medially of the aisles, customers entering the sales room will not have their attention diverted by opposite rows of 45 merchandise to select from but will direct their attention to the merchandise displayed in the cabinets or holders on one side of each path only as they pass through the store. With lower partitions more in the 50 nature of fences, and particularly if the same be tasteful hand rails, the separation of the two streams of customers moving in opposite directions within the paths is equally effective, but it becomes convenient 55 for a person in one path to see and perhaps to stop and visit with a person in the contiguous path. The natural tendency at that time would be for both customers to step up to the fence or rail, and this would take 60 them out of those parts of the paths which are nearer to the cabinets, and hence out of the streams of moving customers. The outer or free end of each fence 20 is preferably provided with a post or column 24 upon 65 which may be mounted a cluster of electric

lights 25 for illuminating purposes. If desired, the upper edge or rail of certain fences 20 may be made of sufficient width to support a line of goods thereon such as bottled pickles or the like, but it is preferable that 70 the same be free of merchandise of any description so as not to detract from the attention of the customers when selecting their goods from the shelves or merchandise holders proper. One or more cabinet units may 75 take the form of a refrigerator 26, in which event the doors 27 thereof will open outwardly into the adjacent paths so that customers may have ready access to the interior of the refrigerator during their passage 80 through the sales room.

Arranged near and extending parallel with the lobby 10 is a checking and settlement department 28, on the counter 29 of which preferably stands an adding machine 85 30 and a cash register 31. The counter 29 is so arranged that the checking and wrapping clerk normally faces the rear end of the store and in position to give attention to the customers as they file past the counter on 90 their way to the exit 13.

Across the back of the lobby is a rack or holder 32 adapted to receive a series of baskets 33 for the use of the customers in carrying the goods selected from the shelves or 95 cabinets in the sales room to the checking and wrapping clerk. It will here be noted that the basket-receiving rack 32 is so arranged that the baskets are exposed at the lobby 10 and in convenient position for customers entering the store to select a basket therefrom prior to entering the sales room through the turnstile 15. It will, furthermore, be noted that inasmuch as the basket-receiving rack 32 is arranged at the rear of 100 and forms a closure for the counter 29, the settlement clerk after removing the articles from the baskets and wrapping and delivering the commodities to the respective purchasers, may conveniently and accurately 105 replace the baskets in the receiving rack 32 without the necessity of the clerk leaving his particular department. The rack 30 is thus accessible to both the settlement clerk and the customers.

Across the rear of the store is a supply or stock room 34 having a plurality of inwardly opening doors 35 which communicate, respectively, with the several aisles 18 and through which the stock clerk may 110 conveniently pass into the supply room for the purpose of replenishing the merchandise on the shelves or holders from time to time as required. Auxiliary display shelves or merchandise holders 36 are preferably arranged against the rear wall 8 on opposite sides of the doors 35, as shown.

The store equipment also preferably includes in its organization a main office or auditing room 38 in which all invoices of 115 120 125 130

stock and other matters of a private business nature are attended to. The office 38 preferably extends longitudinally of the store and is provided with a door 40 which 5 communicates with the settlement department, there being a similar door 41 in the barrier 14 so that access may be readily had to the main office through either the settlement department or lobby by persons having 10 business with the man in charge of said main office. The main office 38 is spaced from the adjacent side wall 5 of the store to form a passage 42 which connects the entrance with the tortuous path through the 15 aisles 18. Also the wall 5 along the passage 42 may be lined with display shelves or cabinets as shown. In order that all of the available floor space may be utilized, the office walls may support display shelves or 20 cabinets 43, certain of which are visible from the passage 42 and others from the first aisle 18 there being a fence 44 extending longitudinally from the rear end of the main office and similar in construction to 25 the rear ends of the fences 20.

Arranged between one end of the settlement department and the wall 6 is a fruit or vegetable rack 45 and extending between said fruit rack and the counter 29 is a guiding 30 partition 46 defining a passageway 47 which communicates with the aisles 18 and also with the exit 13. If desired the lobby 10 may be provided with suitable benches or seats 48 arranged at opposite corners thereof 35 for the convenience of customers entering the store.

It will thus be seen that a customer entering the lobby through the doors 49 will at once be confronted with the basket rack 32 40 and prior to entering the sales room through the turnstile 15 may select one of the baskets from the rack. As the customer passes along the different aisles of the store he makes his desired selection of goods from 45 the merchandise displayed in the shelves or cabinets and deposits the selected goods in his basket and after making the complete circuit of the sales room enters the settlement department through the passage 47. 50 The settlement clerk checks the different articles selected by the purchaser, audits the account and after wrapping the articles delivers the same to the customer, who passes out through the exit turnstile 16, the empty 55 basket being replaced in the receiving rack by the settlement clerk without the necessity of leaving his particular department and in which position the basket may be again used by the next customer entering 60 the store.

The interior arrangement of the merchandise display holders and aisles are such as to effectually utilize the maximum floor space of the store so as to permit customers 65 to conveniently inspect the entire stock of

goods and make selections therefrom in less time than heretofore while the arrangement of the settlement department and basket-receiving rack renders said rack convenient to both the settlement clerk and customers. 70

It will, of course, be understood that the store may be of any desired size or shape and that any desired number of rows of merchandise holders and intervening aisles may be employed without departing from the 75 spirit of the invention.

Having thus described my invention, what is claimed as new is:

1. In a merchandise display room, parallel rows of cabinet units facing interposed 80 aisles, each row composed of two units spaced to leave an opening from aisle to aisle, and fencing in each aisle producing a path from the opening in one row, along the front of one of its units and the corresponding unit in the next row, thence across and along the front of the other unit in the first row and the remaining unit in the next row, and to the opening in the last-named row. 85

2. In a salesroom, rows of cabinets spaced 90 to leave a longitudinal aisle between them, the rows having an inlet-opening into one side of the aisle and an outlet opening from the other side thereof, and a partition rail along said aisle dividing it into paths, the 95 rail being in sections with their inner ends diverted and leading one to one side of said inlet and the other to the opposite side of said outlet, said diverted ends being spaced from each other to produce a "cross-over" 100 path, as described.

3. In a salesroom, two rows of cabinets spaced to leave a longitudinal aisle between them, each row being made up of two units with their inner ends spaced to produce an 105 inlet opening to one side of the aisle and an outlet opening from the other side thereof, a partition rail along said aisle dividing it into paths, the rail being in two sections spaced from each other at the inner ends. 110 and bars connected with the inner ends of said rails and leading oppositely to respectively opposite units in said rows of cabinets, one to one side of said inlet and the other to the opposite side of said outlet, 115 the bars being spaced from each other to produce a "cross-over" path, as described.

4. In a salesroom, two rows of cabinets spaced to leave a longitudinal aisle between them, the rows abutting the end walls of 120 the room and having an inlet opening into one side of the aisle and an outlet opening from the other side thereof, a partition along the aisle dividing it into paths, the partition being in two sections spaced from said room walls at their outer ends to leave "return" paths around them and diverted at their inner ends one to one side of said inlet and the other to the opposite side of said outlet 125 to produce a "cross-over" path, as described. 130

4

5. In a salesroom, two parallel rows of cabinets spaced to leave a longitudinal aisle between them, each row being made up of two units with their outer ends abuttingting the 5 end walls of the room and their inner ends spaced to produce an inlet opening to one side of the aisle and an outlet opening from the other side thereof, a rail along the medial line of said aisle dividing it into 10 paths, the rail being in two sections spaced from each other at their inner ends and spaced from both said room walls at their

outer ends to leave "return" paths around said outer ends, and bars connected with the inner ends of said rails and leading obliquely 15 and oppositely to resceptively opposite units in said rows of cabinets, one to one side of said inlet and the other to the opposite side of said outlet, the bars being spaced from each other to produce a "cross-over" path, 20 as described.

In testimony whereof I affix my signature.

EDWARD L. DA ROZA. [L.S.]
